[57] **CLAIM**

The ornamental design for a carrying case for a night vision binocular, as shown and described.

DESCRIPTION

FIG. 1 is a perspective view of a carrying case for a night vision binocular showing my new design;

FIG. 2 is a front elevational view thereof, the straps being shown broken away in FIGS. 2 through 7 for ease of illustration;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
